(57) **CLAIM**

The ornamental design for a robotic vacuum cleaner, as shown and described.

DESCRIPTION

FIG. 1 is a front view of the first embodiment of a robotic vacuum cleaner, showing the new design;
 FIG. 2 is a rear view thereof;
 FIG. 3 is a top view thereof;
 FIG. 4 is a bottom view thereof;
 FIG. 5 is a right view thereof;
 FIG. 6 is a left view thereof;
 FIG. 7 is a front, top, right perspective view thereof;
 FIG. 8 is a front, bottom, left perspective view thereof;
 FIG. 9 is a rear, top, left perspective view thereof;
 FIG. 10 is a rear, bottom, left perspective view thereof;
 FIG. 11 is a rear, top, right perspective view thereof;
 FIG. 12 is a rear, bottom, right perspective view thereof;
 FIG. 13 is a front, top, left perspective view thereof; and
 FIG. 14 is a front, bottom, left perspective view thereof;
 FIG. 15 is a front view of the second embodiment of the robotic vacuum cleaner;
 FIG. 16 is a rear view thereof;
 FIG. 17 is a top view thereof;
 FIG. 18 is a bottom view thereof;
 FIG. 19 is a right view thereof;
 FIG. 20 is a left view thereof;
 FIG. 21 is a front, top, right perspective view thereof;
 FIG. 22 is a front, bottom, right perspective view thereof;
 FIG. 23 is a rear, top, left perspective view thereof;
 FIG. 24 is a rear, bottom, left perspective view thereof;
 FIG. 25 is a rear, top, right perspective view thereof;
 FIG. 26 is a rear, bottom, right perspective view thereof;
 FIG. 27 is a front, top, left perspective view thereof; and,
 FIG. 28 is a front, bottom, left perspective view thereof.

The portions of the robotic vacuum cleaner shown in broken lines do not form part of the claimed invention.
